CLAIM

The ornamental design for an electronic article surveillance tag, as shown and described.

DESCRIPTION

FIG. 1 is a perspective view of my new design for an electronic article surveillance tag.

FIG. 2 is a front view of my new design for electronic article surveillance tag.

FIG. 3 is a rear view of my new design for an electronic article surveillance tag.

FIG. 4 is a side view of my new design for an electronic article surveillance tag.

FIG. 5 is a side view of my new design for an electronic article surveillance tag.

FIG. 6 is a top view of my new design for an electronic article surveillance tag.

FIG. 7 is a bottom view of my new design for an electronic article surveillance tag.

FIG. 8 is a front perspective view thereof; and,

FIG. 9 is a rear perspective view thereof.

In the drawings, the broken line showing of a security tag cap depicts environmental subject matter and forms no part of the claim.
